UNITED STATES PATENT OFFICE

153,425

DESIGN FOR A REMOTE CONTROL SELECTOR CABINET FOR PHONOGRAPHS

Paul M. Fuller, Buffalo, N. Y., assignor to The Rudolph Wurlitzer Company, Chicago, Ill., a corporation

Application September 8, 1947, Serial No. 141,273

Term of patent 7 years

(CL. D26—14)

To all whom it may concern:

Be it known that I, Paul M. Fuller, a citizen of the United States, residing at Buffalo, in the county of Erie and State of New York, have invented a new, original, and ornamental Design for a Remote Control Selector Cabinet for Phonographs, of which the following is a specification, reference being had to the accompanying drawing, forming part thereof.

In the drawings, Fig. 1 is a perspective view of a remote control selector cabinet for phonographs showing my new design. Fig. 2 is a side elevational view thereof.

I claim:

The ornamental design for a remote control selector cabinet for phonographs, as shown.
PAUL M. FULLER.
